FIG. 17.

INVENTOR

William C. Roe
John H. Roney
His ATTORNEY.

UNITED STATES PATENT OFFICE.

WILLIAM C. ROE, OF PITTSBURGH, PENNSYLVANIA.

PHONOGRAPHIC ATTACHMENT.

Application filed May 5, 1919. Serial No. 294,859.

To all whom it may concern:

Be it known that I, WILLIAM C. ROE, a citizen of the United States, residing at Pittsburgh, in the county of Allegheny and State of Pennsylvania, have invented a new and useful Improvement in Phonographic Attachments, of which improvement the following is a specification.

My invention relates to improvement in phonographic attachments for starting and stopping the mechanism used to rotate the table carrying the record. The object of this invention is to produce a mechanism of this kind having the following characteristics, *viz*:

1. The capacity of starting the mechanism by the movement of the tone arm.
2. Of automatically stopping the machine at the end or completion of any record, regardless of its length and without special or previous adjustment or arrangement, and

Finally, the production of a stop and start mechanism for phonographs having a minimum of parts with a maximum of strength therein, and which can be made at small cost.

I accomplish these objects by means of the device hereinafter more specifically described, reference being had to the accompanying drawings forming part hereof, in which

Figure 1 is a plan view of a portion of the top of the machine,

Figure 2 is a section on line 2—2 of Figure 1;

Figure 3 is a section on line 3—3 of Figure 4;

Figure 4 is a sectional view on line 4—4 of Figure 3;

Figure 5 is a plan view of the frictional washer;

Figure 6 is a central section of same;

Figure 7 is a front elevation of the stop or brake mechanism;

Figure 8 is a plan view of the lower plate or member of the start and stop mechanism;

Figure 9 is a plan view of the intermediate plate thereof;

Figure 10 is a plan view of the top plate or member thereof;

Figures 11, 12 and 13 are side elevations of, respectively, Figures 8, 9 and 10;

Figure 14 is a plan view of a modified form of my invention;

Figure 15 is a section on line 15—15 of Figure 14;

Figure 16 is a plan view of a portion of the top of the machine showing another modified form of my improvement in plan view applied thereto;

60

Figure 17 is a section on line 17—17 of Figure 16.

Referring to the said drawings, and particularly to Figures 1—7 inclusive; 1 is the box or receptacle within which the actuating mechanism of the usual construction is secured. 2 is the table or platform which is centrally mounted upon the spindle 3 which is adapted to be connected with the actuating mechanism (not shown) in the usual manner. The said table is adapted to carry the record 4. 5 is the tone arm of the usual construction and is supported on one side of the box in the usual manner. 6 is a worm gear on one end of the shaft 7 which meshes with the toothed pinion 8 on the spindle 3. The opposite end of said shaft 7 is also provided with a worm gear 9 which meshes with the pinion 10, which is integral with or secured to the thimble 11 which is mounted on the spindle 12. 13 is a toothed pinion loosely mounted on the upper end of the thimble 11, said toothed pinion being free to move in one direction only, when engaged by the serrated or toothed edge of the arm 14, which is connected to and carried by the tone arm 5. 15 is a friction washer mounted on said thimble 11 between the shoulder thereon and the lower side of the loose pinion 13, the function of said washer being to produce sufficient friction to hold the pinion against movement momentarily, whereby the continued rotation of the thimble causes the ball 16 to be wedged against the thimble, locking the pinion 13 to the thimble and causing the shiftable member 17 to move or swerve toward the right to the extent of the play between the teeth of the toothed arm 14, the teeth of the pinion, thus throwing the hooked end of the arm 18 which is integral with the shiftable member 17 out of engagement in the notch *b* in the edge of member 19. Under such conditions the retraction of the spring 20 one end of which is connected to the upwardly projecting prong *c* on said member 19 and the opposite end to the upwardly projecting prong *d* on the member 21 serves to rotate the said member 19, carrying the brake arm 22, which is preferably integral with said member 19 into en-

85

110

gagement with the inner surface of the periphery of the table 2, as shown in dotted lines Figure 1 stopping the same. The said members 19 and 21, with the member 23 and the auxiliary parts thereof, constitutes the stop and start mechanism. The said member 21 comprises a substantially circular plate mounted on the pin 24, on which is also mounted the member 19, the said member 23 having a handle or projecting arm 25, which constitutes the usual stop means, as by throwing the said handle, as shown in dotted lines. Figure 1 carries the highest curved portion *e*, of said member 23 into engagement with the hooked end of arm 18, throwing the same out of engagement with the notch *b*, and permitting the retraction of the spring 20, as heretofore described, to carry the brake arm 22, into contact with the inner surface of the rim of the table, stopping the same. The compression spring 26 one end of which is secured to the upwardly projecting prong *g*, on the member 23 and the opposite end to the prong *d* on member 21, serves to throw the handle 25 into, and out of operative position. Each of said members 19 and 23 are provided with, respectively, recesses *h*, *k* in which the prong *d* on member 21 projects, the length of said recesses limiting the rotary movement of both said members. The spring 27 serves to hold the hooked end of arm 18 in contact with the edge of both members 19 and 23. It will be seen that the member 17 is pivoted on the shaft 3, and that the arm 18 is integral with the member 17, though it may be secured thereto in any suitable manner. It will thus be seen that the rotation of the member 17 will cause a corresponding rotation of the arm 18, the outward extremity of which arm engages the member 19 in the slot *b*.

With this arrangement of my invention, it will be seen that when the phonograph needle is carried into operative engagement with the grooves of the record, the teeth of the arm 14 will pass into engagement with the teeth on the pinion 13. The pinion 13 is arranged to rotate relative to the pinion 10, to permit such engagement between the said teeth on the arm 14 and the pinion 13. The needle having once been placed in operative position, the arm 14 will continue to travel toward the left, (Fig. 1) as a result of the advancement of the needle along the record. However, when the needle reaches the end of the lateral travel, the advancement of the arm 14 ceases. The result is that the pinion 13 is locked into engagement with the shaft 12 through the action of the ball.

The whole member 17 is then rotated on the shaft 3, and the outer extremity of the arm 18 is lifted out of the slot *b* in the

member 19, with the result that the brake is applied.

After a record has been played, the phonograph mechanism may be re-started by merely lifting the needle from the record at the end of the spiral groove thereof and swinging the tone arm to the right to the position indicated by the dotted lines of Fig. 1, wherein the arm 14 engages the trigger projecting in its path which is shown in Fig. 1 and Fig. 9, extending upwardly from the rotatable member 19; the motion of the member 14 further to the right will rotate the member 19 about the point 24 until the hooked end of the lever 18 will fall into the notch *B* on the member 19, the arm 18 being drawn into the said notch by the spring 27.

The rotation of the member 19 will cause the brake arm 22 to move clock-wise about the center 24, and to become disengaged from the peripheral flange of the table 2, where, consequent to the action of the automatic stop mechanism hereinbefore described, said brake arm maintained the brake contact carried at its end in frictional engagement with the platform or turn-table 2 to prevent its rotation. The turn-table will now rotate clock-wise, and the operator will place the needle of the phonograph reproducer in the record groove at the start thereof, whenceforth, the tone arm 5 will be rotated clock-wise to the end of the record, when it will again come to rest and the arm 18 be again moved out of engagement with the member 19 in its slot *b*, and will take a position on the arcuate periphery of the members 19 and 23 substantially at the point marked *e* as indicated in Fig. 1, releasing the rotatable member 19 from its restraining action, and said rotatable member 19 will be propelled to turn-table braking position by the action of the spring 20.

Whenever automatic starting of the turn-table rotation is not desired, the turn-table may be started or stopped by manipulating the handle 25 in the one or the other direction to place the brake 22 into or out of engagement with the turn-table flange.

In Figures 14 and 15 I show a modified form of my invention and which is preferred, on account of its greater simplicity, to that illustrated in Figures 1 to 13 inclusive. In said Figures 14 and 15, 28 is a spindle which is adapted to be connected with the driving mechanism (not shown) in the usual manner. The said spindle is provided with a worm 29, which meshes with a gear wheel 30 on one end of the shaft 31, the opposite end of said shaft having a worm 32 which meshes with and transmits power to the gear wheel 33 which is mounted on the lower end of the spindle 34, the lower end of which is supported in a bearing formed in the shiftable link 35. The oppo-

site end of said link is pivotally connected to and mounted on, one end of the link 36, the opposite end of said link being mounted on the pin 37 and terminates in a handle 38.

5 A thimble 39 is mounted on said spindle 34 and supports a gear wheel 40 loosely mounted on the upper end of said spindle 34. The said gear wheel 40 meshes with the teeth or serrations on the end of the arm 41 which is 10 connected to the tone arm of the machine in a similar manner to arm 14. 42 is an arm one end of which is mounted on the thimble 43 which is mounted on the pin connecting links 35 and 36. The opposite end of said 15 arm terminates in a hooked portion adapted to engage in a notch *n* on the member 44, which member is mounted on the pin 45 and is provided with a handle 46 and a hooked prong 47 adapted to engage over the arm 42.

20 The projecting finger 48 and the brake arm 49 are also provided.

In Figures 16 and 17 I show another modification of my invention. In said figure 50 is the box or receptacle; 51 and 52 are respectively, the table and record thereon; 53 is the spindle adapted to be connected to the operative mechanism in the usual manner. The said spindle has mounted thereon a gear wheel 54 which meshes with and transmits 30 motion to the gear wheel 55 on one end of the shaft 56, the opposite end of said shaft having mounted thereon the worm 57 which meshes with the gear wheel 58 mounted on a pin 59 secured in the plate 60. 61 is a similar 35 gear mounted upon the pin 59 above the gear wheel 58. The said gear 61 meshes with the gear wheel 62 on the spindle 63 which is mounted on one end of the shiftable link 64. The opposite end of said link is connected 40 to the vertically disposed pin 65 to the upper end of which one end of the arm 66 is secured. The upper end of said spindle 63 has mounted thereon the loose gear 67 which meshes with the teeth or serrations on the 45 end of the arm 68, which is attached to the tone arm 69 in a manner similar to arm 14. The said arm 66 projects towards the outer periphery of the table and is provided with a recess *x*, adapted to engage the brake arm 50 69 of the stop and start mechanism. The said stop and start mechanism comprises a plate 70 carrying said brake arm and having an upwardly projecting prong 71 to which one end of a spring 72 is secured, the opposite 55 site end of which spring 72 is connected to a pin in the frame of the machine. The said plate is provided with the usual start lever 73 and the stop lever 74.

Having described my invention what I claim and desire to secure by Letters Patent is:

1. In mechanism for starting and stopping phonographs the combination of the tone arm, an arm carried by said tone arm having teeth or serrations in the outer edge thereof, 60 a shiftable member carrying a loose pinion

adapted to mesh with the teeth on said arm and a fixed gear adapted to receive power from the operative mechanism, in combination with the brake arm and an arm connected with the shiftable member adapted to be thrown out of restraining engagement with the brake arm of the machine to stop the same.

2. In mechanism for starting and stopping phonographs the combination of the tone arm, and an arm carried by and adapted to move with said tone arm, the said last mentioned arm having a plate on the outer end thereof, having teeth or serrations, a shiftable member carrying a pinion loosely mounted on its spindle and adapted to mesh with the teeth on said plate and to be driven by the movement of said arm and a gear fixed on the spindle on which said loose pinion is mounted, an arm connected with said shiftable member, the brake arm means to transmit power to said fixed gear and means to hold the loose pinion stationary while the fixed gear rotates whereby the shiftable member actuates the arm connected therewith to throw said member into, and out of engagement with the brake mechanism to stop and start the machine.

3. In a phonograph having a brake for stopping the record, and having a tone arm, means for automatically operating said brake, said means including an arm pivoted on the record driving shaft, said arm carrying mounted thereon, an auxiliary shaft, one end of the said shaft being provided with a pinion, a gear on said record driving shaft, said pinion permanently engaging the said gear, the other end of said auxiliary shaft being provided with a pinion and a second gear permanently engaging said pinion, said second gear mounted on said auxiliary arm; a toothed segment on said tone arm arranged to engage said second gear, a brake control lever attached to and extending from said auxiliary arm, for holding the brake off to permit the phonograph to run; the said gear on said record driving shaft driven by the record shaft, said gear of the record shaft driving in turn the said auxiliary shaft, said auxiliary shaft driving in turn the said second gear on said arm, said auxiliary shaft being in permanent relation to both of said gears, said second gear arranged when the tone arm is still, to rotate over said toothed segment on said tone arm, whereby the said auxiliary arm may be rotated to operate the brake arm for releasing the brake to stop the phonograph.

4. In a phonograph, having a record driving shaft and a tone arm and a brake, an auxiliary arm pivoted on said record driving shaft, an auxiliary shaft on said arm having a pinion on either end, a first gear on the record driving shaft and a second gear on said auxiliary arm, said auxiliary driving

shaft related to said second gear so that one of the pinions thereon, stands in permanent engagement with said second gear, and the other pinion on said auxiliary driving shaft 5 permanently engages the said first gear and arranged to retain such engagement while the auxiliary arm is rotating about its pivot, a brake controlling arm permanently mounted upon said auxiliary arm for controlling the phonograph brake, a toothed segment on said tone arm adapted to engage said second pinion, whereby the record driving shaft may, through the medium of said first and second gears, and through the 10 medium of said auxiliary driving shaft, rotate the auxiliary arm together with the auxiliary driving shaft and the second gear thereon, to cause the brake controlling arm to operate the brake to stop the phonograph.

20 5. In a phonograph, a brake, a brake controlling arm pivoted on the record driving shaft, an element on said brake controlling arm connected to and rotated by said driving shaft, and means on the tone arm for 25 furnishing traction to the said rotating element to operate the arm for controlling said brake.

6. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 30 brake, and a permanent connection between the driving shaft and the said rotating element.

7. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 40 brake, and means on said arm for preventing the tractive connection between the said brake arm and tone arm from becoming effective while the phonograph is operating.

8. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 50 brake, and a permanent connection between the driving shaft and the said rotating element, and means on said arm for preventing the tractive connection between the said brake arm and the tone arm from becoming effective while the phonograph is operating.

60 9. In a phonograph, a brake, a brake controlling arm pivoted on the record driving shaft, an element on said brake controlling arm connected to and rotated by said driv-

ing shaft, and means on the tone arm for furnishing traction to the said rotating element to operate the arm for controlling said brake, and means on said arm for at times making the tractive connection effective and 70 for making it ineffective at other times.

10. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 75 brake, and a permanent connection between the driving shaft and the said rotating element, and means on said arm for at times making the tractive connection effective, and for making it ineffective at other times.

11. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 80 brake, and a permanent connection between the driving shaft and the said rotating element, and means on said arm for at times making the tractive connection effective, and for making it ineffective at other times.

12. In a phonograph, a brake, a brake controlling arm pivoted on the record driving shaft, an element on said brake controlling arm connected to and rotated by said driving shaft, and means on the tone arm for furnishing traction to the said rotating element to operate the arm for controlling said 90 brake, and a permanent connection between the driving shaft and the said rotating element, and means on said arm for at times making the tractive connection effective, and for making it ineffective at other times, said 95 means including a ball ratchet.

13. In a phonograph, a brake, a brake arm pivoted on the record driving shaft, an element on said brake controlling arm connected to and rotated by said driving shaft, and means on the tone arm for furnishing traction to the said rotating element to operate the arm for controlling said 100 brake, and a permanent connection between the driving shaft and the said rotating element, and means on said arm for at times making the tractive connection effective, and for making it ineffective at other times, said means including a friction element between said record driving shaft and said rotating element. 105

14. In an automatic stopping mechanism for talking machines, the combination of a tone arm adapted to be reciprocated over the record to play the same, of a record-supporting turn-table, driving means therefor, turn-table restraining means adapted to prevent the rotation of the turn-table, operating means for said restraining means responsive to non-movement of the tone arm after a record-playing movement thereof, a lever controlling the respiration of said restraining means to non-operative position, said tone arm being adapted upon a return movement towards starting playing position to actuate said lever to disable said restraining means to again permit rotation of the turn-table of said driving means. 115

15. In an automatic phonograph turn-table controlling mechanism, the combination with a phonograph tone arm, a turn- 120

130

- table for supporting a record, turn-table rotating means, turn-table rotation restraining means, means to automatically operate said restraining means responsive to a cessation 5 of tone arm movement, and means to subsequently disable the said restraining means, said disabling means being adapted to be actuated by the motion of the tone arm towards the playing starting position.
- 10 15. In an automatic phonograph turn-table controlling mechanism, the combination with a reciprocatory phonograph tone arm, a turn-table for supporting a record, turn-table rotating means, turn-table rotation restraining means, and means to disable the said restraining means, said disabling means being adapted to be actuated by the motion of the tone arm, and means responsive to the stopping of the tone arm when 15 the tone arm reaches the end of a record, automatically operable to cause actuation of the said restraining means.
16. In a phonograph mechanism, a rotatable turn-table, a tone arm, and means controlled by the reciprocatory movement of the tone arm to cause the starting of the turn-table rotation, and means responsive to stopping of the tone arm during turn-table rotation to discontinue such rotation.
- 20 25 30 35 17. In a phonograph, a phonograph driving shaft, a reciprocatory tone-arm, a phonograph stopping brake and a brake controlling arm, an element on said brake controlling arm connected to and rotated by said driving shaft, and means on the tone arm for furnishing traction to the said
- rotating element responsive to stopping of the tone arm while said shaft is rotating to cause it to operate the said brake controlling arm. 40
18. In a phonograph, a reciprocatory tone arm, a record support, driving means therefor, a brake, a brake controlling arm, an element for said brake arm adapted to be idly rotated by said driving shaft during 45 the normal playing operation of the phonograph, means on the tone arm for furnishing traction to the said rotating element to move the arm for operating said brake, and means on said arm for causing 50 the tractive connection between the said brake arm and the tone arm to become effective while the phonograph driving means is operating in a predetermined length of time after said tone arm is stopped. 55
19. In a phonograph, a brake and a brake controlling arm, an element on said brake arm connected to and rotated by said driving shaft, and means on the tone arm for furnishing traction to the said rotating element to operate the arm for controlling said brake, and means on said arm for at times making the tractive connection effective, and for making it ineffective at other times. 60
- In testimony whereof, I have hereunto 65 signed my name in the presence of two subscribing witnesses.

WILLIAM C. ROE.
